WINDOW OR DOOR ASSEMBLY

Sidney Fuller Sparkes, Scarborough, Queensland, Australia

Application August 21, 1956, Serial No. 605,381

Claims priority, application New Zealand August 25, 1955

1 Claim. (Cl. 20—19)

This invention relates to a window or door assembly, and it has more particular reference to an assembly having slidable window or door panes.

The principal object of the invention is to provide a window or door assembly of the type having panes adapted to be moved slidably between positions in which they act to open or close the window or door, the assembly being of such improved construction that a relatively large number of panes may be employed and may be compactly arranged in open positions to provide a very effective window or door opening.

Another object of the invention is to provide a window or door assembly of the aforesaid type of such construction that the connections between adjacent panes in the closed positions will be desirably weatherproof.

Yet another object of the invention is to provide a window or door assembly of the abovementioned construction which may be operated simply and easily between the open and closed positions of the panes, and in which the panes may be safely held in desired open positions.

A further object of the invention is to provide a window or door assembly of the character described wherein novel forms of slidable panes are employed to suit the various materials from which the panes may be suitably made.

Still further objects of the invention are to provide a window or door assembly of the type stated which may be employed, with either vertically or horizontally sliding panes, in all cases where sliding windows or doors may be used, whether externally or internally of buildings, and including floor-length and sill-type windows and cupboard and partition doors; the assemblies being relatively simple and inexpensive to manufacture and install, yet strong and durable in operation.

Other objects and advantages will be apparent from the following description.

In the drawings:

Fig. 1 is a rear perspective view of one form of assembly according to the invention, usable either for windows or doors, but shown particularly in relation to sill-type windows;

Fig. 2 is a sectional end view along the line 2—2 of Figure 1;

Fig. 3 is a perspective view of part of one of the vertical guide rails of the assembly shown in Figures 1 and 2;

Fig. 4 is a partly broken-away perspective view of part of one of the panes of the assembly shown in Figures 1 and 2;

Fig. 5 is a front elevational view along the line 5—5 of Figure 2;

Fig. 6 is a sectional end view of an alternative construction of the drainage tray of the assembly shown in Figures 1 and 2, this form of drainage tray being most suitable for floor-length windows or doors;

Fig. 7 is a perspective view of part of an alternative construction of the guide rail shown in Figure 3;

Fig. 8 is a partly broken-away perspective view of an

alternative construction of the pane shown particularly in Figure 4;

Fig. 9 is a rear perspective view of a further form of assembly according to the invention, usable either for windows or doors in any location, but shown particularly in relation to partition doors, and

Fig. 10 is a sectional plan view along the line 10—10 of Figure 9.

In the drawings, the embodiment of the invention shown in Figures 1 to 5 includes a rectangular frame 10 within which four panes 11 are mounted, an uppermost pane 11a being fixed while a lowermost pane 11b and two intermediate panes 11c are vertically slidable within the frame 10 to positions in which they are banked behind the uppermost pane 11a.

The frame 10 includes a pair of upright guide rails 12 of extruded metal, each guide rail 12 having five parallel channels 13 along its inner portion, and formed also with front and rear flanges 14. As illustrated in Figure 3, each channel 13 is more or less heart-shaped in plan view so that, when a pane 11 is accommodated therein, the pane will bear only along the vertical lines through the three points indicated at 15 in Fig. 3.

Each pane 11 is made of transparent plastic material such as that sold under the trademark "Alsynite," and it is in the form of a flat sheet with integral top and bottom flanges 16 and 17 respectively which are formed on opposite sides of the pane 11 and are of opposed hook-like form so that the lower flange 17 of one pane may engage beneath the upper flange 16 of another pane. At the same time, each of the flanges 16 and 17 is cut away at both of its ends so that its length is equal to the distance between the upright guide rails 12, and so that the portion of each end of the pane 11 which may engage in a channel 13 of the guide rail 12 is of suitable rectangular cross-section, this cutting-away of the flanges 16 and 17 being apparent from Figure 4 of the drawings.

The lower extremities of the guide rails 12 are mounted in a drainage tray 18 secured on a window sill 19, each guide rail 12 resting on a flat base 20 of the tray 18 with its front and rear flanges 14 bearing against an up-turned end flange 21 of the tray 18. At the rear of the tray 18, the metal of the base 20 is turned upwards for a short distance and then downwards to be secured to the rear of the sill 19 so that there is formed a rear drainage flange 22. Each of the upright guide rails 12 is held in place on the drainage tray 18 by a bolt 23 passing through apertures in the front and rear flanges 14 of the rail 12 and through the drainage flange 22.

The upper ends of the guide rails 12 are interconnected by a frame top member 24 which has a flat horizontal top 25 with front and rear down-turned flanges 26 and 27 respectively. The top member 24 is secured in place on the guide rails 12 by means of bolts 28 securing the ends of the flanges 26 and 27 of the top member 24 to the flanges 14 of the guide rails 12.

As shown in Figure 2 in particular, the lowermost pane 11b is located slidably in the rearmost channel 13 of the guide rail 12, while the other three panes are arranged in series above the pane 11b and progressively to the front of the assembly in the other channels 13, the top flanges 16 of the bottom three panes engaging with the bottom flanges 17 of the top three panes, while the bottom flange 17 of the lowermost pane 11b bears against the base 20 and drainage flange 22 of the drainage tray 18. On the other hand, the top flange 16 of the uppermost pane 11a is hooked wedgedly over an attachment flange 29 of a pane-supporting bar 30 so that the pane 11a is fixed against movement in its channel 13. As shown in Figures 2 and 5, the pane-supporting bar 30 extends between and is secured at either end to the front of the guide rails 12, and the attachment flange 29 fits closely between the

rails 12 and slopes backwardly and upwardly from the bar 30 and then extends vertically for a short distance as illustrated.

There is provided an aluminium ventilation pane 31 located in the opening in the frame 10 between the front flange 26 of the top member 24 and the pane-supporting bar 30. The ventilation pane 31 is hingedly connected to the flange 26, and for this purpose, the lower part of the flange 26 has a cut-away portion 32 at its middle as shown in Figure 5, while it has hinge portions 33 at either end, turned arcuately under. The upper edge of the ventilation pane 31 is correspondingly cut away at its ends adjacent the hinge portions 33, while its middle portion 34 is turned arcuately over and forwards so that a hinge rod 35 may extend between the guide rails 12 through the hinge portions 33 and 34. The ventilation pane 31 extends down below the top of the uppermost pane 11a to slightly above the pane-supporting bar 30, and it has side flanges 36 adapted to bear against the front faces of the guide rails 12 to effect weather-proofing.

To move the ventilation pane 31 hingedly about the hinge rod 35, there is provided an adjustment bolt 37 hingedly connected to a bracket 38 on the ventilation pane 31 so that it is free to hinge in a vertical plane. The rear end of the adjustment bolt 37 passes threadedly through an adjustment knob 39 which has an integral body portion 40 supported in a forked bracket 41 by a pin 42. The bracket 41 is secured to the top member 24 of the frame 10 and has its fork engaging in a circumferential recess in the body portion 40 with the pin 42 also in the recess. By this arrangement, the knob is free to rotate in the bracket 38, to advance the bolt 37, and at the same time it is free to hinge in the vertical plane through the bolt 37 to accommodate upward movement of the front end of the bolt 37 when the ventilation pane is hinged outwards.

So that the panes 11 may be raised or lowered in their channels 13, there is provided an actuating arm 43 on a bracket 44 secured to the front face of the lowermost pane 11b, near to its bottom. The arm 43 is of sufficient length to extend forwards past the middle channel, and it has a rubber pad 45 secured to its top. It will be apparent that the lifting of the lowermost pane 11b will cause the pad 45 to engage successively beneath the intermediate panes 11c so that the three panes 11b and 11c may be raised to positions in rear of the uppermost pane 11a with the pad 45 in contact with the lower edge of the uppermost pane 11a.

To raise or lower the lowermost pane 11b to effect opening or closing of the window in the abovementioned manner, there is provided an elevating mechanism associated with the frame top member 24 and adapted to be operated by a control cord 46. The elevating mechanism includes a pair of shafts 47 and 48 mounted rotatably through the flanges 26 and 27 at opposite sides of the top member 24, the shaft 47 being longer than the shaft 48 and extending rearwards of the flange 27, and having secured to its inner end a pulley wheel 49 on which the control cord 46 is wound. The pulley wheel 49 has ratchet teeth formed around its periphery adapted to be engaged normally by the upper end of a pawl 50. The pawl is pivoted, as shown in Figures 1 and 2, about a pivot rod 51 extending rearwards from a bracket 52 on the flange 27, and its lower end below the pivot rod 51 has a substantially horizontal lug 53 with an aperture through which the control cord 46 passes. The pawl 50 is normally maintained with its upper end engaging one of the teeth of the pulley wheel 49 by virtue of the provision of a tension spring 54, one end of which loosely encircles the shaft 47 while the other end is connected to a lug 55 on the upper end of the pawl 50. It will thus be apparent that the control cord 46 may be pulled down at any time to rotate the shaft 47 with the pulley wheel 49 acting as a ratchet in conjunction with the pawl 50, and when the cord 46 is

released, the spring 54 will ensure that the pawl 50 firmly engages with a tooth of the pulley wheel 49 to prevent counter-rotation. However, the pulley wheel 49 may be released from the pawl 50 at any time to allow counter-rotation of the shaft 47 merely by so moving the cord to one side that it moves the lug 53 to pivot the pawl 50 away from the pulley wheel 49 against the action of the spring 54, the amount of counter-rotation of the shaft 47 then being controlled by tension exerted by the operator on the cord 46.

On the shaft 47 within the top member 24 there are removably secured a lifting pulley 56 and a sprocket wheel 57. Identical pulleys and sprocket wheels are also removably secured to the other shaft 48, and, as indicated by the dotted lines in Figure 5, a chain 58 connects the sprocket wheels 57 of the two shafts 47 and 48. Thus, rotation of the shaft 47 by means of the control cord 46 will cause rotation in the same direction of the shaft 48, and there are wound around the lifting pulleys 56 of the two shafts 47 and 48 lifting cords 59 which extend downwards on corresponding sides of the pulleys 56 to be connected to lifting lugs 60 secured to the lowermost pane 11b. For convenience, the lifting lug 60 shown on the right in Figure 1 is riveted through the pane 11b to the bracket 44 of the actuating arm 43.

A spring-type catch 61 of conventional design is mounted on the drainage flange 22 of the drainage tray 18 and is adapted to engage a locking lug 62 connected to the lifting lug 60 whereby the lowermost pane 11b will normally be locked when it is in its closure position. However, the catch 61 may be digitally released to free the pane 11b to allow it to be raised by the control cord 46.

The assembly may be easily installed in a window opening in a wall by mounting it in the manner described on the window sill 19 and securing the top member 24 and guide rails 12 to the appropriate members defining the opening in the wall. For this purpose, screws may be passed, if desired, through the top 25 of the top member 24 or through the flanges 14 of the guide rails 12, or else attachment plates or brackets of any desired type may be used to extend between the flanges 14, 26 and 27 and the adjacent portions of the wall.

The operation of the assembly will be apparent from the foregoing description, the parts being arranged either in the closed positions shown in Figures 1 and 2 in which good weatherproofing will be afforded by the inter-engagement of the flanges 16 and 17 of the panes 11, or with the panes 11b and 11c elevated by the actuating arm 43 to desired extent up to a maximum height in which they lie in banked formation behind the uppermost pane 11a. At the same time, the ventilation pane 31 may be opened to desired extent by means of the adjustment knob 39.

Although the assembly has been illustrated and described in its application to sill-type windows, it will be apparent that it is equally applicable to floor-length windows or doors, or to wide garage doors or the like in which the panes may be suitably made of opaque material. There is illustrated in Figure 6 an alternative construction of drainage tray 18 which is most suitable for floor-length windows or doors, the base 20 of the drainage tray 18 being mounted on the floor 63, where it has flat extremity 64 secured to the floor.

It will also be apparent that the guide rails 12 and panes 11 may be modified to suit the materials from which they are to be made. In Figure 7, there is illustrated a guide rail made of pressed metal sheeting instead of extruded metal as in the form previously described and illustrated particularly in Figure 3. In this modified guide rail 12, each channel 13 has parallel sides 65 against which the panes 11 may slide, while the inner extremity of each channel is bent back as indicated at 66 to reduce

the bearing surface contacting the ends of the panes 11 and thereby reduce friction in the same manner as is provided for in the extruded form of guide rail.

Furthermore, it will be apparent that the panes 11, as previously described, in which there are integral top and bottom flanges 16 and 17, cannot be made of plate or other glass. Accordingly, there is illustrated in Figure 8 an alternative construction of pane which may be suitably made of glass. In this case, there is provided a rectangular pane frame 67 having identical upper and lower extruded bars 68 with engagement flanges 69 extending from one side thereof, the bars 68 being arranged so that the flange 69 of the lower bar, the flanges 69 terminating short of the ends of the bars 68 in the same manner as previously described in relation to the plastic panes. A pane of glass 70 is located in longitudinal channels 71 of the bars 68 and terminates at either end short of the ends of the bars 68 but past the ends of the flanges 69. Identical side bars 72 have inner channels into which the ends of the glass pane fit, and their upper and lower ends are reduced in cross-section to fit within the longitudinal channels 71 of the upper and lower bars 68 to which they are secured by counter-sunk rivets 73. The overall width of each side bar 72 in the direction of the glass pane 70 is equal to the depth of the guide rail channel 15 in which it is to be slidably mounted, so that its inner edge is in line with the ends of the flanges 69. If desired, the glass pane 70 may be set in rubber within the channels of the frame 67. It will be seen that the pane illustrated in Figure 8 will thus be functionally equivalent to the construction shown in Figure 4.

Again, it may be preferred, in certain instances, to provide a simple, manually-operated assembly without the cord and pulley-type mechanism shown in Figures 1 and 2. In such a case, a handle (not shown) may be secured to the lowermost pane 11b whereby the panes may be raised to desired extent, and a number of spaced grooves may be provided in the upright rails 12 within any selected one of which a slidable bolt (not shown) on the lowermost pane may be releasably engaged to support the panes at a desired height.

In Figures 9 and 10 of the drawings, there is shown an alternative form of assembly according to the invention, in which horizontally sliding panes are used, the assembly being usable for sliding doors or windows in any location, although it is most applicable to partition doors in the form illustrated.

In this assembly, a rectangular frame 74 includes upper and lower guide rails 75 between which four panes 76 mounted, the left side pane 76a being fixed while the right side pane 76b and two intermediate panes 76c are horizontally slidable within the frame 74 to positions in which they are banked behind the left side pane 76a.

The guide rails 75 are pressed from sheet metal so that each has front and rear flanges 77 and four parallel channels 78, as illustrated, within which the panes 76 are slidably mounted. Vertical end members 79 and 80 constitute the left and right hand ends of the frame 74 respectively, these end members also being pressed from sheet metal with front flanges 81, rear flanges 82 and intermediate weatherproofing flanges 83. As shown in the drawings, the weatherproofing flange 83 of the left end member 79 is adapted to fit into slots 84 between the outer two channels 78, while the flange 83 of the other end member 80 is similarly adapted to fit into a slot which in this case however is located between the inner two channels 78.

Each pane 76 is made of transparent plastic material in the form of a flat rectangular sheet, and there are affixed to both ends of the intermediate panes 76c, to the right end of the pane 76a and to the left end of the pane 76b engagement strips 85 of extruded metal. These strips 85 are substantially F-shaped in cross-section, so that each may engage over the end of a pane and have a flange 85a extending at right angles to the pane, adapted to en-

gage with an oppositely disposed flange 85a of an adjacent pane 76 as illustrated in Figure 10.

The strips 85 terminate short of the top and bottom of each pane 76, extending between the top and bottom guide rails 75 but not into the channels 78.

The left hand end of the pane 76a is secured by screws to the weatherproofing flange 83 of the left end member 79 so that it is fixed in position and a weather-proof connection is made at this end. The right hand end of the pane 76b may bear in the closed position against the rear of the flange 83 of the right end member 80, but the pane 76b is free to slide to the left.

So that the panes 76 may be moved slidably in their channels 78, there is provided an actuating arm 86 on a bracket 87 secured to the front face of the pane 76b, near to its right hand end, the arm 86 being of sufficient length to extend past the second outermost channel 78. It will be apparent that the movement of the pane 76b in its channel towards the left hand end will cause the arm 86 to engage successively with the strips 85 on the right hand ends of the panes 76c so that the three panes 76b and 76c may be moved to positions in rear of the pane 76a, with the actuating arm 86 located adjacent the right hand end of the pane 76a.

To move the pane 76b to effect opening or closing of the door in the abovementioned manner, there is provided a handle bracket 88 for manual operation; and in order that the pane 76b may be held in closed position when desired, there is provided a catch 89 adapted to be engaged with a locking lug 90 on the handle bracket 88.

This form of assembly may also be installed very easily in a similar manner to that described in relation to the first embodiment; and if desired or found necessary in cases of external doors for example, a drainage tray may be provided beneath the bottom guide rail 75 for weather-proofing purposes.

Door or window assemblies made in accordance with the invention will therefore be found most effective in achieving the objects for which the invention has been devised. It will however be understood that the particular embodiments of the invention hereinbefore described may be subject to many minor modifications of constructional detail and design. Any desired number of window or door panes may be employed with a corresponding number of guide channels, and they may, for example, be made to house ball or other bearings along their contact surfaces in the guide channels to allow more efficient sliding. These and other modifications will be readily apparent and are deemed to reside within the scope and ambit of the invention, as defined by the appended claim.

What I claim is:

A window or door assembly including a frame, a plurality of panes mounted slidably in the frame for traveling in separate parallel paths within the frame, means for supporting the panes either in closure positions in which they are arranged in series to close the way through the frame or in a common open position in which they are arranged evenly in stacked superposed formation at one end of the frame to open the way through the frame, each pane having a first flange adjacent an edge thereof which is closer to such common open position and extending away from an immediately succeeding pane, the latter being adapted for further movement away from such open position, each pane having a second flange adjacent the opposite edge thereof extending in a direction toward said succeeding pane, whereby in moving away from the open position, the second and first flanges of adjacent panes interlock to move each pane successively to its closure position, each such succeeding pane being free to move throughout its separate path independently of the immediately preceding pane of such series and without interference to the open position to effect the evenly stacked formation, an arm member on the pane adapted for furthermost travel from such common open position to engage the edge of each pane adjacent the second flange thereof, and means for sliding said furthermost

pane between its closure and open positions to engage said arm member with each of the remaining panes and return them to such evenly stacked formation at the open position.
